UNITED STATES PATENT OFFICE.

GOTTLÖB AICHELE, OF NELLINGEN, NEAR ESSLINGEN, GERMANY.

SHIFT MECHANISM FOR TYPEWRITING MACHINES.

Application filed January 23, 1924. Serial No. 687,904.

To all whom it may concern:

Be it known that I, GOTTLÖB AICHELE, a citizen of the State of Wurttemberg, Germany, residing at Nellingen, near Esslingen, 5 Wurttemberg, Germany, Kaiserstrasse 2, have invented certain new and useful Improvements in Shift Mechanism for Typewriting Machines, of which the following is a specification.

10 It has heretofore been proposed to provide those parts of a typewriter whereby the shifting of the type bar supporting segments is limited, with elastic insertions to dampen and reduce the noise, but practical experience has shown that such insertions, after a short time, are deformed in such a way that the path covered by the typebasket or segment in the recurring shifting adjustments is lengthened; as a result of this the lines of 15 typewritten matter are rendered at least partly uneven and undulatory, and the appearance to the eye is more or less impaired, especially where large upright capitals are employed.

20 The object of my invention is to provide a novel means whereby this drawback is obviated; the means referred to may comprise a stationary guide provided with a preferably inclined slot and a slide subjected to the action of springs acting in opposite directions and having a slot inclined oppositely to the slot of the guide, said slide being in engagement with the system of levers forming the shifting mechanism of the typewriting machine. The arrangement is such that the shifting of the type bar supporting segment is limited by the slot which is provided in the slide. This arrangement and combination of parts may be modified in such a way 25 that the direction of the end sections of the slot deviates from the main part thereof in order to reduce the size of the abutment surface.

30 My invention is illustrated, by way of example, in the accompanying drawing, in which Figure 1 is a side-view of the shifting mechanism for shifting the type-bar supporting segment for upper and lower case printing; Figure 2 is a cross-section of Figure 1; Figure 3 is a separate view of the parts shown in the right-hand lower part of Figure 1, some of said parts being in another position; and Figure 4 is a similar 35 illustration showing the movable parts in still another position, as is all more fully described hereinafter.

Referring to Figure 1, *a* is a double-armed shift-key having a finger key *a'*, *c* a double-armed intermediate lever, and *b* a thrust-rod, through the medium of which the lever *c* is rocked when the shift-key *a* is depressed. *r* is a pin on the shift-key *a* whereby the motion of said shift-key *a* is transmitted to the rod *b*, and *s* is a pivot connecting the parts *b* and *c* with each other. *t* is the supporting 60 pivot of the lever *c*. The pivot *s* serves also for connecting the parts *b* and *c* with a member *d* which carries the type-lever supporting-segment or case shift element *e*; to the latter are attached, in known manner, the type-bars *f* provided with the types *f'* bearing the characters *h* and *i*, of which either the lower ones (*i*) or the upper ones (*h*) engage the paper passing over the platen or roller *g*, according to the position of the 65 shifting mechanism.

From the rear end of the lever *c*, a link *h* extends obliquely downwards and is provided at its lower end with a small roll *l* movable in a stationary slot *m* formed in a 70 stationary casing or guide *v* and extending at an inclination corresponding approximately to the oblique normal position of the link *h*; the casing *v* is fixed in place upon the frame *z* of the typewriter by screws *z'* or other suitable fastening means. The roll *l* is of sufficient axial length to project also into a slot *m'* provided in a slide *n* movable in the guide casing *v*, said slot *m'* being inclined at right angles with respect to the slot *m*. The slide *n* is subjected to the action of an upper spring *o* and of a lower spring *p*, both springs being tensile springs and opposing each other; that is to say, in the normal condition of the parts, the spring *o* 75 is contracted and the spring *p* is extended as indicated in Fig. 2, while, when the parts are in the upper case printing position the spring *o* is extended and the spring *p* is contracted, as shown in Fig. 4. The spring *o* is guided by a pin *x* and the spring *p* is guided by a pin *y*, both pins serving also to guide the slide *n* in its movements in the casing *v* which, as previously stated, is affixed to the frame part *z* by screws *z'*. One end 80 of the spring *o* is suitably connected with the frame *z* and the other end thereof is suitably connected with the slide *n* so as to be stretched in the intended manner as the slide *n* descends from its normal position; similarly, the one end of the spring *p* is attached 85 in any suitable way to the slide *n* and its

other end is fixed to the frame z in any suitable way, so that said spring p will be stretched in the manner intended as the slide n rises in a return movement toward its normal position. It will be understood that the pin x is rigidly secured to the frame z and that the slide n slides thereon while the pin y is carried by the slide n and slidably moves in the frame z .

10 When the key a' of the shift-key a is depressed, in order to raise the types f' so as to cause the characters i to be impressed upon the paper, instead of the characters h , the lever c is pivotally rocked and the link h is depressed. This causes the roll l to move downwardly in the slot m and to exert a camming action upon the walls of the slot m' whereby the slide n is moved downwards in the guide casing v . This downward motion is assisted by the pulling action of the tensile spring p in passing from the extended position of Fig. 2 to the contracted position of Fig. 4, the tensile spring o being at the same time correspondingly stretched 25 from a contracted position to an extended position, and thus to a progressively increasing degree opposing the downward movement of the slide n . Because of this downward movement, the position of the slot m' relatively to the slot m changes, so that when the parts are in an intermediate position the two slots cross each other, as illustrated in Figure 3.

When the parts reach their final positions, 30 as shown in Figure 4, the roll l is in its end position in the lower end of the slot m and the upper end of the slot m' , and the slide n has arrived in its lowest position. The spring o has now been stretched and attained 35 its maximum tension and by its gradually developed resistance to the drop of the slide n and its associated parts brings the same to rest without noise and any appreciable shock. When the movable parts move in 40 the opposite direction, the slide n is at first drawn upwards by the spring o , which upward movement the spring p opposes to a progressively increasing degree, as it is gradually stretched from the contracted position shown in Fig. 4 back to the extended 45 position of Fig. 2, so that when the roll l approaches its other end position, the tension of said spring p has been developed to an extent sufficient to check the motion 50 of the movable parts which thus re-

sume their normal position without appreciable shocks or jars.

I claim:

1. In a typewriting machine, the combination of a supporting segment, a stationary guide member having an oblique slot, a slide arranged in said guide member and having also an oblique slot, which crosses said other slot, a lever operatively connected at one end with the segment of the typewriting machine, a link operatively connected with the other end of said lever and means provided on said link for engaging both of said slots simultaneously.

2. In a typewriting machine, a case shift element, means for selectively shifting said element from a normal position to a case shift position, a shiftable means operatively connected to the case shift element, and resilient means on opposite sides of said shiftable means for providing a gradually increasing resistance respectively to the shifting movements of said element from its normal position and to its return movements to said normal position to neutralize impact shocks incidental to such shifting and return to normal position.

3. In a typewriting machine, the combination of a support for a plurality of type bars having upper and lower case characters thereon, shifting mechanism whereby said support is shifted to selectively bring the upper and lower case characters into printing positions, a stationary guide casing provided with an inclined slot, a slide movable in said casing and provided with a slot inclined in the opposite direction to that of the casing, a link operatively connected with said shifting mechanism, a roller carried by said link and extending into said slots for moving said slide in accordance with the shifting movements of said shifting mechanism and opposed springs for developing a progressively increasing resistance to the shifting movements of said slide in each direction whereby shocks incidental to the operation of the shifting mechanism are neutralized.

In testimony whereof I affix my signature in presence of two witnesses.

GOTTLOB AICHELE.
